[57] **CLAIM**

The ornamental design for a disposable container for storing and dispensing a stack of identical card-mounted key blanks, as shown and described.

DESCRIPTION

FIG. 1 is a perspective view from the front and side of a disposable container for storing and dispensing a stack of identical card-mounted key blanks showing my new design;

FIG. 2 is a top plan view of the container shown in FIG. 1;

FIG. 3 is a bottom plan view thereof;

FIG. 4 is a right side elevational view of FIG. 1;

FIG. 5 is a front elevational view thereof;

FIG. 6 is a rear elevational view thereof; and,

FIG. 7 is a left side elevational view of FIG. 1.

The broken line in FIG. 3 represents tear line.
